United States Patent Office

Des. 217,757

Patented June 9, 1970

217,757

BOTTLE

Edward Charles Kozlowski, 74 Columbine Drive, Trumbull, Conn. 06611, and Jack Duncan Campbell, 52 Norwood Ave., Northport, N.Y. 11768

Filed Jan. 6, 1969, Ser. No. 15,223

Term of patent 14 years

Int. Cl. D9—01

U.S. Cl. D9—20

FIG. 1

FIG. 2

FIG. 3

FIG. 4

FIG. 1 is a perspective view of a bottle, showing our new design;

FIG. 2 is an elevational view, the opposite side being the same in appearance as the side shown;

FIG. 3 is an elevational view looking from the right of FIG. 2, the opposite side being the same in appearance as the side shown; and

FIG. 4 is an enlarged fragmentary view of the ornamental area shown in the FIGS. 1-3.

We claim:

The ornamental design for a bottle, as shown and described.
